UNITED STATES PATENT OFFICE.

ISRAEL A. POSNER, OF PROVIDENCE, RHODE ISLAND.

DESIGN FOR A FINGER RING.

Application filed September 17, 1925. Serial No. 14,803. Term of patent 7 years.

To all whom it may concern:

Be it known that I, ISRAEL A. POSNER, a citizen of the United States, residing at Providence, in the county of Providence and State of Rhode Island, have invented a certain new, original, and ornamental Design for a Finger Ring, of which the following is a specification.

In the accompanying drawings the figure is a plan view of a finger ring embodying my invention.

A feature of this design is the contrasting colors of the adjacent angular ornaments.

I claim:

The ornamental design for a finger ring, as shown and described.

ISRAEL A. POSNER.
